UNITED STATES PATENT OFFICE.

IVAN GOSAR, OF BETHLEHEM, PENNSYLVANIA.

CURTAIN AND SHADE SUPPORT.

1,351,289.

Specification of Letters Patent. Patented Aug. 31, 1920.

Application filed August 28, 1919. Serial No. 320,428.

To all whom it may concern:

Be it known that I, IVAN GOSAR, a citizen of the United States, residing at Bethlehem, in the county of Northampton and State 5 of Pennsylvania, have invented certain new and useful Improvements in Curtain and Shade Supports, of which the following is a specification.

This invention relates to a combined lace 10 curtain and window shade support, and an object of the invention is to provide a device of this nature which may be easily and conveniently attached to the frame of a window, without marring the window frame in any 15 visible portion thereof, and also to provide a lace curtain and window shade support which will be artistic and which eliminates the necessity of the employment of pins, rings or hooks or analogous articles for 20 supporting the lace curtains, eliminating the liability of tearing the curtain and also to provide a device by means of which the curtain may be quickly and easily attached thereto.

More specifically the invention comprehends the provision of an ornamental frame 25 which is adapted to be mounted upon the top of a window frame or casing and which ornamental frame carries suitable supporting brackets for carrying the ordinary spring roller of a window shade and also carries a pair of substantially L-shaped arms which are pivotally connected to the ornamental frame and engage in recesses 30 formed therein for forcing and securely clamping the lace curtain connected to the ornamental frame and also to provide suitable lockers for retaining the substantially L-shaped members in firm gripping engagement 35 with the curtain.

A further object of the invention is to 40 provide means whereby the ornamental frame may be quickly and easily attached to and removed from about the upper end of a window frame or casing, which means will not mar or scar the window frame in any 45 way leaving the frame in substantially the same condition as it was originally after the curtain and shade supporting ornamental 50 frame is removed therefrom.

Other objects of the invention will appear 55 in the following detailed description taken in connection with the accompanying drawings forming a part of this specification and in which drawings:

Figure 1 is a front elevation of the improved ornamental curtain and shade support showing it applied to a window frame.

Fig. 2 is a rear elevation partly in section of the improved curtain and shade supporting frame. 60

Fig. 3 is a horizontal section partly in plan of the improved curtain and shade supporting frame.

Fig. 4 is a cross section through the frame 65 taken on the line 4-4 of Fig. 1.

Fig. 5 is a detail view illustrating the bracket structure employed for pivotally connecting one of the curtain gripping L-shaped rods to the ornamental frame. 70

Fig. 6 is a detail perspective view of a part of the attaching catch structure.

Fig. 7 is a detail perspective view of one 75 of the brackets for supporting the shade roller, and

Fig. 8 is a detail view of a part of the catch structure which is driven into the upper surface of a window frame.

Referring more particularly to the drawings, wherein like characters indicate like and 80 corresponding parts throughout the several views, the frame 10, which is adapted to fit about the upper portion of a window frame or casing as indicated at A may have any suitable design thereon, as indicated at 11, 85 to add to the attractive appearance thereof, or it may be perfectly plain as desired, and this frame 10 includes an outer portion 12 and angularly disposed end portions 13 carried thereby and extending at right angles 90 to the outer face portion 12, of the frame 10. This frame is hollow and it has a pair of substantially L-shaped members 14 attached to its upper surface at the inner end 95 of the end portion 13 thereof, the said catch 95 member having the outer edges of their lengths 15 rolled, and bent downwardly as shown at 16, the edges being serrated, providing a plurality of teeth 17 which are adapted to engage over staples 18 which are 100 driven into the upper surface of the window frame A, short distances inwardly from the end thereof, and these teeth 17 engaging over the upper edges of the staples 18 will hold the frame 10 connected to the window 105 frame A.

Attached to the inner surfaces of the end portion 13 of the ornamental frame 10 directly opposite each other are brackets 19 and 20, the lower depending ends 21 of 110

which are shaped in the same manner as the approved type of bracket employed for supporting shade rollers, and these brackets 19 and 20 are adapted to support the spring 5 roller 22 of ordinary approved construction which carries the shade 23. The brackets 19 and 20 are provided with attaching portions 24, which are connected to the depending portions 21, by horizontal portions 25, facing the depending portions 21 inwardly from the inner surfaces of the end portion 13, so as to space these depending portions 21 from each other, properly to receive the supporting pin at the ends of the shade rollers 22, allowing shade rollers of ordinary construction and length to be used in connection with the improved shade and curtain support.

Substantially L-shaped bolts 27 are 20 threaded into the end portion 13, and they have wear washers or disks 28 mounted upon the upright portions thereof and engaging the upper surface of the horizontal portion 29, upon which plate the rolled end 25 30 of substantially L-shaped curtain clamping rods 31 are placed. These rolled eye ends 30 extend over the vertical or upright portions of the L bolts 27, the bolts forming pivotal supports therefor, and they are prevented from moving longitudinally off the 35 upper end of the bolt by angled brackets 33. The brackets 33 having attaching prongs 34 formed thereon adapted to be driven into the frame 10. However, they may be attached in any suitable manner.

The frame 10 is recessed, in its inner surface as shown at 34' for partially receiving the L-shaped rods 31 therein, for clamping the lace curtain C securely in place and 40 connecting them to the frame 10 without requiring the use of rings, screws, hooks, or analogous structures which are apt to tear the curtain. The L-shaped curtain clamping rods 31 are held in curtain gripping positions by buttons or latches 36, which are rotatably carried by suitable pins 37 and are substantially semi-circular shaped in plan, as clearly shown in Fig. 2 of the drawings 45 so as to permit them to be moved into and out of engagement with the L-rod 31, to permit these rods to be swung outwardly upon their pivots as indicated in dotted lines in Fig. 3 of the drawings, to permit the disconnection of the lace curtain B from the 50 support. The inner facing ends of the rods 31 are outturned as shown at 38, and the inner facing ends of these rods 38 are recesses as shown at 39, to permit the engagement therein of the ball of a curtain 55 finger to facilitate the opening or moving outwardly of the L-shaped rods to release a window curtain.

Changes in details may be made without departing from the spirit of this invention; 60 but,

I claim:

1. In a combined curtain and shade support, the combination of an ornamental frame adapted to be mounted about the upper end of a window casing, and having its 70 end portion engaging the end portion of the casing, and its face faced outwardly from the outer face of the casing, means carried by said ornamental frame for attaching it to the window casing, shade roller 75 supporting brackets carried by the ornamental frame, and curtain attaching means carried by said ornamental frame.

2. In a combined curtain and shade support, the combination of an ornamental 80 frame adapted to be mounted about the upper end of a window casing, and comprising a face portion and angular end portions, a pair of substantially L-shaped rods pivotally connected to said angular end portions 85 and adapted to clamp curtains between the rod and the inner surface of the ornamental frame, and buttons carried by the frame for engaging said rods to hold them in curtain clamping position.

3. In a combined curtain and shade support, the combination of an ornamental frame adapted to be mounted about the upper end of a window casing, and comprising a face portion and angular end portions, a 90 pair of substantially L-shaped rods pivotally connected to said angular end portions and adapted to clamp curtains between the rod and the inner surface of the ornamental frame, buttons carried by the frame for engaging said rods to hold them in curtain clamping position, said ornamental frame provided with a recess into which said L-shaped rods are adapted to clamp curtains.

4. In a combined curtain and shade support, the combination of an ornamental frame including a face portion and angular end portions adapted to engage against the ends of a window casing, said face portion adapted to be positioned outwardly of the outer surface of the upper end of the window casing, toothed attaching plates carried by the upper surfaces of said end portion for attaching the ornamental frame to the window casing, shade roller supporting brackets carried by the inner surfaces of the ends of said ornamental frame, and curtain attaching means pivotally carried by said frame.

5. In a combined curtain and shade support, the combination of an ornamental frame including a face portion and end portions, said ornamental frame adapted to be mounted about a window casing, attaching brackets carried by the ornamental frame, a pair of substantially L-shaped rods pivotally connected to the ends of the ornamental frame, said ornamental frame provided with recesses in its inner surface adapted to receive portions of said rods 130

therein for clamping curtains in the recesses and connecting them to the ornamental frame, at the inner surfaces thereof.

6. In a combined curtain and shade support, the combination of an ornamental frame including a face portion and end portions, said ornamental frame adapted to be mounted about a window casing, attaching brackets carried by the ornamental frame, 5 a pair of substantially L-shaped rods pivotally connected to the ends of the ornamental frame, said ornamental frame provided with recesses in its inner surface adapted to receive portions of said rod therein for

clamping curtains in the recesses and connecting them to the ornamental frame at the inner surfaces thereof, the meeting ends of said L-shaped rods being outturned and concavely curved to provide a hook for receiving the ball of an operator's fingers to 15 permit the swinging the rods outwardly to disconnect a curtain from the ornamental frame, and buttons carried by the inner surface of the ornamental frame for engagement with said rods to hold them against 20 accidental pivotal movement. 25

IVAN GOSAR.
